UNITED STATES PATENT OFFICE.

GEORGE W. TODD, OF OMAHA, NEBRASKA.

DENTAL BRIDGE.

1,171,368.

Specification of Letters Patent.

Patented Feb. 8, 1916.

Application filed April 24, 1915. Serial No. 23,575.

To all whom it may concern:

Be it known that I, GEORGE W. TODD, a citizen of the United States, residing at Omaha, in the county of Douglas and State 5 of Nebraska, have invented certain new and useful Improvements in Dental Bridges, of which the following is a specification.

This invention relates to an improvement in dental bridges, and has for one of its objects to provide metallic clasps of such form 10 that they will present surfaces of greater area than ordinary for being connected when disposed side by side, so that the bridge may have an adequate strength by 15 using a limited quantity of metal.

Another object is to produce U-shaped, metallic clasps having brace-bars arranged to prevent spreading, and provided with parallel ridges disposed in a manner to 20 adequately sustain stresses directed longitudinally of the teeth.

The invention also has reference to the provision of porcelain teeth of such form that they may be conveniently mounted 25 upon or removed from the metallic clasps.

While the invention is illustrated in connection with dental bridges, the metallic clasps and teeth may be used to advantage for dental plates.

In the accompanying drawing which 30 illustrates the invention, Figure 1 is a side view of a procelain tooth. Fig. 2 is a rear view of the same. Fig. 3 is a transverse section on line 3 3 of Fig. 1. Fig. 4 is an 35 end or top plan view of a metallic clasp. Fig. 5 is a view in longitudinal section of a metallic clasp on line 5 5 of Fig. 4. Fig. 6 is a front view of a bridge constructed in accordance with the invention. Fig. 7 is a 40 rear view of the bridge shown in Fig. 6. Fig. 8 is a sectional view of the bridge on line 8 8 of Fig. 7. Fig. 9 illustrates a modified form of the invention, showing a side view of a tooth and clasp, parts being broken 45 away and in section.

Referring now to the drawing, numerals 10 indicate teeth constructed of porcelain or other suitable material, their bases *a* being of conventional saddle-shape so that they 50 will conform substantially to the surface of the gums upon which they are to be normally seated, the front part of each tooth preferably being of greater length than the rear part as shown in the drawing. In each 55 tooth a groove *b* is formed in each of its sides midway between its front and back

and extending near to its top, a second groove *x* being formed in its base opening on the grooves *b*, and each tooth is provided with a recess *c* of substantially semi-circular form extending longitudinally of the tooth from near its top to open on its base, and which extends forwardly to open upon the grooves *b*; and preferably grooves *b* are formed upwardly convergent from the 60 base as best shown in Fig. 1.

Numerals 11 indicate metallic holders or clasps each consisting of an attenuated, curved plate *d* substantially of U-shape in cross-section, each wing thereof, at its end, 70 being provided with an inwardly projecting ridge *e*, the lower ends of said ridges being connected by a transversely disposed reinforcing strip *f*, each curved plate having a form corresponding to that of a recess *c* 75 and the ridges and reinforcing strip conforming respectively to the shape of the grooves *b* and *x* of a tooth, and, when assembled, the metallic parts of the clasp which have been mentioned are adapted to 80 substantially fill the grooves and recess of a tooth.

To form the bridge shown in Figs. 6, 7, and 8, solder is employed for connecting the clasps side by side, and the clasps may 85 be soldered to the crowns 12; and after the teeth have been mounted in the metallic clasps, the bridge will be complete.

The convergent form mentioned for 90 grooves *b* is desired since this feature facilitates the mounting of the teeth in the clasps after the metallic parts of the bridge have been prepared. Cement is preferably 95 employed for connecting the procelain teeth with the clasps. On account of the convergence mentioned for grooves *b* the stresses directed longitudinally of the teeth will normally tend to press them inwardly of and therefore to be firmly held by the clasps, the ridges *e* co-operating to advantage for 100 sustaining the stresses, and strips *f* preventing spreading of the ridges *e* or sides of the clasps. In instances where gold is employed the construction is of particular advantage since the stresses are directed end-wise of the ridges and clasps, and therefore 105 a lesser quantity of expensive metal than ordinary may be used.

According to the described construction, 110 the use of pins or lugs may be dispensed with and cement depended upon for connecting each tooth with its clasp, and this

is an adequate holding means, especially for the front teeth. By this construction any porcelain tooth may be readily removed from the bridge by a dentist by moving it outwardly and parallel with ridges *e*; and a new tooth may be inserted by moving it inwardly toward the base of the bridge and substantially parallel with said ridges.

Fig. 9 illustrates the use of lugs or pins, 10 all other parts being the same as already described, and the use of pins is not considered to be a departure from the invention since they may be inserted after the teeth have been placed in the clasps, suitable apertures *h* and *k* being provided respectively in the clasp and the tooth, the pins *m* being used, if desired, for securing the molars or larger teeth to the clasps.

I claim,—
20 In devices for the purpose described, the combination of a plurality of teeth each having grooves formed in its sides between

its front and back extending from near its top to open on its base and a second groove formed in a space opening on the first 25 named grooves, and provided with a recess in its back and sides extending from near its top to open on its base and said first named grooves, a plurality of connected clasps each having a curved part with opposed inwardly projecting ridges and a transversely disposed reinforcing strip connecting said ridges, said teeth being adapted to be mounted upon said clasps, the curved part and the ridges of a clasp engaging respectively in a recess and the first 30 named grooves of a tooth, said reinforcing strip engaging in the second groove thereof.

In testimony whereof, I have affixed my signature in presence of two witnesses.

GEORGE W. TODD.
